UNITED STATES PATENT OFFICE.

CLARENCE E. FILE, OF PARSONS, KANSAS.

FILE.

Application filed May 20, 1922. Serial No. 562,375.

To all whom it may concern:

Be it known that I, CLARENCE E. FILE, a citizen of the United States, residing at Parsons, in the county of Labette and State 5 of Kansas, have invented new and useful Improvements in Files, of which the following is a specification.

This invention relates to filing devices and has for its object the provision of a 10 novel file designed for use by lawyers in keeping together all the papers pertaining to a given case, various separate envelope compartments being provided for holding the pleadings, correspondence, case papers, 15 notes and other data and the file furthermore having a certain space upon which it is designed that the authorities cited in the given case be noted.

An important object is the provision of a 20 file of this character in which the various small envelopes for holding the different types of papers are affixed to the main container, the main container itself being so constructed as to be folded and to inclose 25 all the envelopes so that a compact and neat file will result.

An additional object is the provision of a file of this character which will be simple, and inexpensive in manufacture, efficient, 30 time saving and accurate in use and a general improvement in the art.

With the above and other objects and advantages in view the invention consists in the details of construction to be hereinafter 35 more fully described and claimed and illustrated in the accompanying drawings, in which:

Figure 1 is a perspective view of the file in closed position,

40 Figure 2 is a view of the inside showing the file opened up,

Figure 3 is a perspective view showing the inside of the file when partly opened,

45 Figure 4 is a fragmentary elevation of the file,

Figures 5, 6 and 7 are elevations of the envelopes or containers used in conjunction with the invention; and

50 Figure 8 is a fragmentary elevation of the device showing the series of envelopes or containers arranged with their flaps extending horizontally or at right angles to the flaps of the envelopes or containers shown in Figure 2.

55 Referring more particularly to the drawings I have shown the file as comprising a

jacket 10 which is formed of cardboard of suitable size and thickness and which is folded along its center line 11 so as to enclose the papers which are stored within the 60 auxiliary compartments or envelopes to be described. One edge of the folded jacket is formed with a tab 12 upon which may be inscribed a number referring to the case or the names of the plaintiff and defendant 65 so that proper identification of the file is easy.

The front of the outside of the jacket bears the name of the file and is provided with legends as to the court, county and 70 State with blank lines opposite these legends upon which the data may be filled in. Also inscribed on the file are legends relating to the filing of the various pleadings together with data lines referring to pleadings and 75 other lines referring to the orders, these lines being of course written upon in accordance with the data in the given case. There are also provided other lines for the replies, date of trial, the verdict and date 80 of the verdict, a line for the motion for new trial, etc. These various legends might be arranged in any preferred order and might vary more or less without departing 85 from the spirit of the invention.

Inscribed upon one inside face of the jacket is the legend "Authorities" below which are ruled lines 13 upon which may be quoted the various authorities or cases 90 cited as references in the given case to which the file applies. Secured upon the lower end of this same side of the jacket is an envelope 14 of ordinary type designed for the reception of memorandum cards etc., this legend being provided upon the flap 15 of 95 the envelope.

Disposed against the other inside face 16 of the jacket is a series of superposed envelopes 17, 18 and 19 which may be secured to the jacket in any desired manner as for 100 instance by means of the paper fasteners 20 illustrated. These envelopes are of progressively decreasing size so that the ends of the lower ones will project beyond the ends 105 of the envelopes above to be visible when the jacket is open. These projecting ends of the envelopes 17, 18 and 19 bear respectively the legends "Pleadings," "Correspondence" and "Case papers and data notes etc." These envelopes might be anyone of 110 a large number of types though it is preferable that they have their flaps 21, 22 and

23 respectively secured by means of cords 24 which are secured to buttons 25 on the flaps and wrapped about other buttons 26 on the envelopes. The various envelopes 5 are preferably labeled "Pocket 1," "Pocket 2" and "Pocket 3."

The face 16 of the file is inscribed at its top with the legend "Miscellaneous, briefs, etc." and it is intended that briefs and other 10 papers not classified be placed against this face of the jacket beneath the superposed small envelopes.

From the foregoing description and a study of the drawings it will be apparent 15 that I have thus provided a simply constructed and consequently inexpensive file which will be highly advantageous for use by lawyers in keeping the records and all papers in their cases, the file being of such 20 construction that the various papers of different types may be kept separate and in their proper respective places so that they will be readily accessible at a moment's notice without hunting through a heterogenous 25 conglomeration, so that a wonderful saving in time and labor will be effected.

While I have shown and described the preferred embodiment of the invention it is

of course to be understood that I reserve the right to make such changes in the form, construction and arrangement of parts as will not depart from the spirit of the invention or the scope of the subjoined claims. 30

Having thus described my invention I claim:

1. A file including a sheet of stiff material creased longitudinally to form complementary sections, a plurality of superimposed envelopes each of which being slightly smaller than the other so that their upper 40 ends project one above the other, and a common fastening passing through the envelopes to one of the sections.

2. A filing device including a sheet of stiff material creased longitudinally to form a 45 pair of complementary sections, a plurality of superimposed envelopes arranged upon one of the sections with their flaps extending longitudinally of the latter and having their upper ends arranged in stepped relation, and fastenings extending through the inner longitudinal edges of the envelope and one of the sections. 50

In testimony whereof I affix my signature.

CLARENCE E. PILE.
